UNITED STATES PATENT OFFICE.

BORIS PODOLSKY, OF LOS ANGELES, CALIFORNIA.

APPARATUS FOR STARTING HEATERS.

1,326,137.

Specification of Letters Patent. Patented Dec. 23, 1919.

Application filed May 19, 1919. Serial No. 298,284.

To all whom it may concern:

Be it known that I, Boris Podolsky, a citizen of the United States, residing at Los Angeles, in the county of Los Angeles and

5 State of California, have invented new and useful Improvements in Apparatus for Starting Heaters, of which the following is a specification.

This invention relates to a timed controlled apparatus for starting heaters, and is more particularly adapted to be used in connection with an alarm clock for starting an electric heater at a predetermined time.

The object of my invention is to provide 15 an efficient means for automatically starting an electric heater at a predetermined time, and for also sounding an alarm to awake the occupant of the room at a predetermined time after the heater has been started.

20 A further object of my invention is to provide an apparatus which will coöperate with an alarm clock, whereby when the clock is set to sound an alarm at a particular time, the heater starting mechanism will also be 25 set to start the heater at the same time or at any desired period previous to the time at which the alarm is set.

I accomplish the above and other objects by means of the apparatus herein described and illustrated in the accompanying drawings, in which:

Figure 1 is a back view of any well known type of alarm clock showing my improved apparatus applied thereto, parts being 35 broken away to show more clearly part of the interior mechanism.

Fig. 2 is a side elevation of the same, part of the casing being broken away in order that the application of my apparatus may 40 be more clearly understood.

In carrying out my invention I employ an alarm clock 4, of any well known type, which is provided with the usual alarm setting stem 5 carrying the pointer 6 adapted 45 to coöperate with the usual dial 7 to indicate the time at which the alarm is to be sounded.

The shaft 8 which carries the minute hand of the clock and is adapted to make one revolution each hour, is provided with the pinion 9 which is cut in the surface of said shaft, and consequently revolves therewith. Journaled loosely on the shaft 8 at a point just below the pinion 9 and supported between 55 the collars 10 and 11 which are secured to said shaft, is the annular disk 12, provided

with the upwardly extending annular flange 13 which carries on its outer surface the gear teeth 14, and on its inner surface the gear teeth 15.

60 Pivoted loosely around the shaft 8, at a point just above the pinion 9, and held against lateral movement between the collars 16 and 17 which are secured to said shaft, is a sleeve 18, having a radially extending arm 19, which is provided with the downwardly extending stem 20, upon which is loosely journaled the gear 21, adapted to mesh with the pinion 9 and the internal gear teeth 15. A gear 23 is rigidly secured 65 to the alarm setting stem 5 and meshes with the teeth 14 on the disk 12.

70 Formed in the back of the clock, are a pair of segmental slots 25 and 26 and disposed in parallel relation. Arranged to slide in the slot 25 is the segmental block 28, which carries the pointer 29 adapted to rest upon the outer surface of the back of the clock and coöperate with the graduation 75 marks 30, which represent fractions of an hour in quarters. The block 28 also carries an arm 31 adapted to rest upon the inner surface of the back of the clock, which in turn is provided with an electric contact brush 32 properly insulated therefrom. 80 Threaded into the arm 31 and passing outwardly through the slot 26 is the knurled headed screw 33.

85 By the above described arrangement it will be clearly seen that when it is desired to move the pointer 29 to register with any of the graduation marks 31, it will be only necessary to loosen the screw 33 and move the block 28 around in the slot until it reaches the desired point and then tighten 90 the screw again.

95 Referring to Fig. 1, 35 represents the power lines connected to any suitable source of electrical energy. The brush 32 is connected to the positive side of the power line 100 by the wire 36. A brush 37 adapted to wipe against the shaft 18, is secured to a post 38 mounted on the back of the clock; and a wire 39 runs from said post to an electric magnetic coil 40, the free end 41 of said wire terminating at a contact button 42. An armature 43 adapted to coöperate with the coil 40 is pivoted at 44 and is provided on its end with the brush 45 adapted to normally contact with the button 42. Another contact 110 button 46 is arranged in the path of the brush 45, and has a wire 47 leading there-

from to an electrical heater 48, shown in diagram, which in turn is connected to the positive side of the power line by the wire 49.

The arm 19 is provided with a contact 5 finger 50 adapted to engage with the brush 32 at predetermined intervals.

The operation of my apparatus is as follows: The alarm mechanism is set in the usual manner, by moving the pointer 6 in 10 the direction indicated by the arrow A to the desired hour at which the alarm is to be sounded, and in so doing the gear 23 actuates the gears 14, 15 and 21 to move the arm 19 an equal number of degrees in the direction indicated by the arrow B, said gears being properly proportioned for this purpose. The pinion 9 on the minute hand shaft 8 meshing with the gear 21, causes the arm 19 to move in the direction of the arrow 15 B one-twelfth of the cycle every hour, the gear teeth 14 and 15 being locked against movement by the gear 23 for this purpose.

As illustrated in Fig. 1 the time of day is twelve o'clock and the alarm is set to sound 25 at six o'clock, it will therefore be seen that when the hour hand has reached six o'clock the alarm will be sounded and at the same time the arm 19 will have advanced just one-half of its cycle, until the contact point 50 30 secured thereon engages with the brush 32, thereby closing the electric circuit through the magnetic coil 40 to shift the armature 43, thus closing the circuit through the heater 48. When it is desired to close the circuit through the heater at any time previous 35 to the time the alarm is sounded the pointer 29 and brush 32 are moved in the slot 25 to an advanced position. Thus it will be seen that the heater may be started at any 40 predetermined time previous to that at which the alarm is sounded.

It will be seen that by the foregoing description that I have provided a simple and efficient apparatus whereby an electric heater 45 may be automatically started at any predetermined time and may be located in any desired room or part of the building other than the room in which the alarm clock is located, thus warming the room previous

to the time the alarm of the clock has sounded 50 to awaken the sleeper.

What I claim is:

1. An apparatus of the class described, comprising means for sounding an alarm, and means coöperating with said alarm for 55 starting a heater at any predetermined interval from the time the alarm is sounded.

2. The combination with an alarm clock provided with alarm setting mechanism, of means associated with said alarm setting 60 mechanism and the clock movement for starting a heater, and means whereby said heater starting means may be regulated with respect to said alarm setting mechanism and 65 clock movement.

3. The combination with an alarm clock provided with alarm setting mechanism, of a heater interposed in an electric circuit, of an electric contact switch in said circuit 70 geared to said alarm setting mechanism and the clock movement, and an adjustable contact brush in said electric circuit arranged in the path of said contact switch, whereby when the alarm setting mechanism is adjusted to sound the alarm at a predetermined 75 time, the contact switch and brush will coöperate to close the electric circuit to start the heater at a predetermined interval from the time the alarm has sounded.

4. The combination with an alarm clock 80 provided with alarm setting mechanism, of a heater interposed in an electric circuit, of a switch in said electric circuit mounted on the shaft of the minute hand of said clock and adapted to normally move with said 85 shaft, of mechanism interposed between said switch and said alarm setting mechanism whereby said switch may be moved on said shaft in exact ratio to the movement of said alarm setting mechanism, and an adjustable 90 brush interposed in said electric circuit and disposed in the path of said switch whereby when said brush and switch contact, the electric circuit will be closed to start said heater.

In witness that I claim the foregoing I 95 have hereunto subscribed my name this 8th day of May, 1919.

BORIS PODOLSKY.
